See application file for complete search history.

FIG. 1 is a front view of a headset showing an embodiment of our new design;

FIG. 2 is a rear view thereof;

FIG. 3 is a left-side view thereof;

FIG. 4 is a right-side view thereof;

FIG. 5 is a top view;

FIG. 6 is a bottom view thereof; and,

FIG. 7 is a perspective view thereof.

Any shading and cross-hatching are not features of the design but are utilized to illustrate the surface contours of the headset in the drawings. The broken lines in the drawings depict parts of the headset that form no part of the claimed design.
